UNITED STATES PATENT OFFICE.

JAMES F. DUFFY, OF SOUTH CHICAGO, ASSIGNOR OF ONE-HALF TO AUGUSTUS D. LAMB AND FRANCIS W. NEWLAND, BOTH OF CHICAGO, ILL.

REHEATING-FURNACE.

SPECIFICATION forming part of Letters Patent No. 253,916, dated February 21, 1882.

Application filed June 13, 1881. (No model.)

To all whom it may concern:

Be it known that I, JAMES F. DUFFY, a citizen of the United States, residing in South Chicago, county of Cook, and State of Illinois, 5 have invented a certain new and useful Reheating-Furnace, of which the following is a specification.

This invention relates to improvements in furnaces for reheating iron or steel bars, tools, &c., and in which said bars and tools are suspended over and subjected to the direct action of the products of combustion, and to blasts of air from one or more tuyeres.

In furnaces of this class it has heretofore been the practice to introduce one or more tuyeres or air-pipes directly into the fire-chamber, and as a result the air and consequently the heat of the furnace is greater at the point of entrance of the tuyeres than at any other portion 15 of the furnace, or between any two of a series of these tuyeres. The effect of thus concentrating, instead of diffusing, the heat is to heat to a high degree that portion of a steel bar or tool directly over the tuyere, while other portions 20 of the bar remote from the tuyere remain at comparatively a low temperature, and as a result the temper of the bar or tool is rendered variable, and its quality consequently deteriorated. Skilled labor has been employed to move 25 the bar back and forth, or to manipulate it so as to as far as possible evenly heat it; but this mode of operation is not only expensive, but not altogether successful.

The object of my invention is to avoid these 35 objections by providing means for evenly distributing the blast of air from the tuyeres or air-pipes before coming in contact with or penetrating the fuel or products of combustion in the fire-chamber, and thereby promote combustion and cause a uniformity of and even 40 distribution of the heat generated over the entire surface of the fuel and area of the fire-chamber, so that the bars or tools to be treated will be evenly heated without requiring any 45 manipulations or change of place in the furnace. I attain these objects by devices illustrated in the accompanying drawings, in which—

Figure 1 is a perspective, with parts broken away, of a furnace embodying my invention;

and Fig. 2, a vertical longitudinal section of 50 the same.

Similar letters of reference indicate the same parts in the figures of the drawings.

A represents the front, B the rear, and C the side walls, of my furnace, which is provided with an arched or reverberatory top, D, 55 provided with perforations d, to permit unconsumed gases to escape, said walls and top being of the ordinary construction, and of brick or other suitable material.

In the front end and toward the top of the furnace is a vertically-sliding door, E, having at its base a broad ledge or shelf, e, serving as a support-rest for the outer ends of the bars to be treated, while one or more doors, G, upon 60 the side or arch of the furnace, admit of inspection or removal of the articles.

Below the shelf, and near the bottom of the furnace, is the ash-pit door H, and entering the side of the furnace is an air-pipe or tuyere, I, 70 which may be one of a series entering the sides and ends of the furnace for supplying blasts of air to and through the burning fuel and rising products of combustion.

So far the furnace described is of the construction ordinarily used for reheating bars of iron, steel, and a variety of small tools, except that usually a ledge is formed above the surface of the fuel for supporting the latter articles and the ends of the bars; but as my object is to diffuse or spread the blasts of air, and consequently the heat over the entire fire-chamber, I provide an open rectangular and perforated fire-box, K, which, when in use, is filled with coke, coal, or other suitable fuel. 75 This fire-box is of less dimensions than and is supported above the bottom and from the sides of the furnace, so that a surrounding air space or chamber, L, is formed for the free circulation and spreading out of the blasts of 80 air before entering the box. The perforations are of sufficient size to permit a free circulation of the air through them and extend over the entire bottom, but those upon the sides and ends are preferably near the bottom, as shown, 85 so that the blasts of air will be caused to enter the fire-chamber below the surface of the burning fuel, it being understood that the air-pipes 90

or tuyeres will deliver the blast upon the outside of and between the perforations in the box, so that the blast will be spread out, and circulating through the chamber, will then pass 5 through the perforations to the fuel.

The top of the air-chamber is closed by a rim or ledge, *l*, connecting the upper edge of the fire-box which rises to a level with the furnace-door with the walls of the furnace, said 10 ledge forming a shelf or support for the ends of the bars and for small articles to be reheated.

Below the bottom of the fire-box, and dividing the air-chamber at that point, is a perforated plate, *M*, conforming in area to the bottom 15 tom of the fire-box, and having its perforations *m m* alternating with those in the bottom of the fire-box, as shown in Fig. 2, so that currents of air which may be introduced through the openings *n n* in the front of the furnace 20 and below the plate, or through air-pipes, will be divided and diffused over the entire bottom before passing through the fire-box.

From the above description it will be understood that by thus dividing and spreading out 25 the currents or blasts of air uniform combustion is produced throughout the entire contents of the fire-box, and consequently an even temperature is maintained in the combustion-chamber, which is that portion of the furnace above 30 the surface of the fuel, and particularly at that portion of it where the bars or tools are placed.

As before stated, the result of having such an even temperature is to entirely do away 35 with any necessity of skilled labor for manipulating the articles, and, moreover, of watching them further than to determine when they have attained the desired heat.

The fire-chamber and plate just described to illustrate my invention are constructed of plate metal; but I wish it to be understood that I 40 do not limit myself to this particular material, for it is obvious that the equivalents of said chamber and plate may be built of brick, and the openings or perforations be formed by honeycombing the same, without departing 45 from the spirit of my invention, the main object in either construction being to spread the heat, so that the bars and tools will be evenly heated throughout their dimensions.

What I claim, and desire to secure by Letters Patent, is—

1. The combination in reheating-furnaces, with a perforated fire-box, having a perforated plate arranged below and between said fire-box and the tuyeres to obtain an even distribution of heat, of a surrounding ledge to receive the articles to be heated. 55

2. A heating-furnace consisting of the perforated fire-box, the furnace-walls, an air-chamber surrounding said fire-box, and air-inlets entering said chamber, as and for the purpose set forth. 60

3. A reheating-furnace consisting of the perforated fire-box, the air-chamber surrounding said box, the air-inlets of a perforated plate arranged below and between said fire-box and the tuyeres, and said tuyeres, substantially as and for the purpose set forth. 65

JAMES F. DUFFY.
